UNITED STATES PATENT OFFICE.

GEORGE L. HOXIE, OF UPPER MONTCLAIR, NEW JERSEY.

PROCESS OF AND APPARATUS FOR CRACKING OILS.

1,418,713.

Specification of Letters Patent. Patented June 6, 1922.

Application filed August 9, 1918. Serial No. 249,077.

To all whom it may concern:

Be it known that I, GEORGE L. HOXIE, a citizen of the United States, and a resident of Upper Montclair, in the county of Essex and State of New Jersey, have invented certain new and useful Improvements in Processes of and Apparatus for Cracking Oils, of which the following is a full, clear, concise, and exact description, such as will enable others skilled in the art to which the invention relates to make and use the same, reference being made therein to the accompanying drawings, which form a part of this specification.

My invention relates to the treatment of liquid hydrocarbons such, for example, as petroleum, in the crude form in which it is obtained from the earth, or after a part of the more volatile constituents thereof have been removed therefrom by fractional distillation; the object of said treatment or process being to increase the amount of lighter and more volatile hydrocarbons obtained from a given quantity of crude or partially refined petroleum or crude oil. In processes of the class to which my invention relates the liquid hydrocarbon is heated to a comparatively high temperature, which results in the decomposition or breaking up of some of the constituents of the hydrocarbon being treated, after which the volatile products thus produced are collected and condensed; such processes being commonly referred to as "cracking" processes, the purpose of which is to increase the yield of the more volatile products, such as gasoline and similar light hydrocarbons, obtainable from a given quantity of crude petroleum or similar liquid hydrocarbon.

The objects of my invention are to provide an improved process or method of treatment, and an improved apparatus or device suitable for performing the said process, whereby the quantity of light liquid hydrocarbons, that is, those boiling below a fixed boiling point assumed as the maximum boiling point desirable, obtainable from a given quantity of crude oil is materially increased; to provide an improved method and apparatus in which the production of undesirable liquid hydrocarbons, such for example as those boiling at a temperature too high for efficient use in an internal combus-

tion engine on the one hand or too volatile for storage or convenient use on the other, is reduced to a minimum; to provide an improved process and means for working the same which may be operated continuously, which may be readily controlled, and one in which the product produced will be of uniform quality so long as the operation of the process is continued; to provide a process which may be readily and cheaply carried out, and an apparatus for conveniently and with facility performing the process; and to provide other improvements in and relating to the processes commonly known and referred to as cracking processes for increasing the yield of the lighter liquid hydrocarbons obtainable from a given quantity of crude petroleum.

In cracking processes heretofore in use the usual practice has been to heat the entire mass of liquid hydrocarbon being operated upon to a high temperature, that is to a temperature which, from experience, has been found to increase the yield of liquid hydrocarbons which boil at a comparatively low temperature, as in the case of gasoline, and then separate the light or more volatile hydrocarbons from the mass of hydrocarbon thus treated.

As distinguished from the old processes above outlined, my improved process contemplates the heating to a temperature sufficient to accomplish the cracking of the liquid hydrocarbon operated upon of a small volume of said liquid, and then adding said small quantity of heated and more or less completely cracked hydrocarbon to a much larger volume of comparatively cool liquid hydrocarbon and mixing the same therewith; whereby the heated liquid is suddenly cooled, the cracking action is entirely or for the most part arrested, and the small volume of liquid hydrocarbon subjected to the action of the heat together with such volatile products as may have resulted from such heating are rapidly dispersed throughout a large mass of similar liquid at a much lower temperature.

The temperature of the larger volume of liquid hydrocarbon is kept substantially lower than the temperature best suited for cracking the liquid being operated upon; and the said larger mass in the carrying out

of my process in its preferred form, and by means of the preferred form of apparatus provided for that purpose, and after the process is in operation; is made up of fresh 5 untreated liquid hydrocarbon, of liquid hydrocarbon which has been subjected to a cracking temperature but the volatile products thus produced not separated therefrom, and of heavier liquid hydrocarbon the residue 10 due left after driving off the more volatile constituents from previously heated liquid, and which residue is being continually worked over.

It therefore follows that in the carrying 15 out of my improved process small quantities of liquid hydrocarbon are being continually heated to a cracking temperature and that said small quantities are immediately, and without attempting to separate the more 20 volatile products thus produced therefrom, added to and mixed with and more or less dispersed throughout a much larger volume of liquid hydrocarbon maintained at a much lower temperature; there being no attempt 25 to separate the light or volatile hydrocarbons produced by the heating from the identical volume of liquid subjected to the cracking temperature as by distilling them off at or substantially at the cracking temperature, and under such conditions as to 30 pressure as may be necessary in order to accomplish the distillation of such light hydrocarbons at the inordinately high temperature required for the most effective cracking 35 of the liquid being operated upon.

The particular mass of liquid subjected to the cracking temperature, or rather continual succession of small masses so treated as will hereinafter appear, is thus immediately 40 mixed with and dispersed throughout a much greater body of cooler liquid of a similar character; and is thus cooled before any attempt is made to separate the more volatile products produced by the cracking step of the process therefrom, and while such products are in a nascent condition.

This sudden cooling of the liquid which has just previously been heated to such a 50 temperature such that it was being cracked or decomposed into more volatile products arrests the cracking operation, and the un-cracked portion of the liquid in question as well as the lighter or cracked products produced by the heating become merged with and dispersed throughout the larger mass of cooler hydrocarbon while the lighter products are in a nascent state or condition, as it were, and before they have separated, 55 as vapors or otherwise, from the heated liquid from which they were formed. After 60 this cooling and mixing step or operation the said light and volatile products are driven off or distilled from the total volume 65 or liquid hydrocarbon produced by mixing

the smaller cracked constituent thereof with the larger and cooler mass, as above pointed out.

The distillation process or step may be carried out in part or wholly in the container within which the highly heated liquid hydrocarbon is mixed with the larger volume of cooler hydrocarbon; for the temperature of the mixture will, after the process has been in operation for a time and 70 because of the continual addition thereto of the highly heated liquid, rise to a point above the boiling point of the lighter hydrocarbons produced in carrying out the process, whereupon they will obviously pass 80 off from the mixture in the form of a vapor which may be condensed by any suitable condenser. I prefer, however, to withdraw the mixture produced as above from the mixing receptacle and subject the same to a distillation process in a separate still; in which case the cracking of the liquid hydrocarbon and mixing the same with a large volume of cooler similar liquid, and the separation of the lighter hydrocarbons from the mixture 85 thus produced, are separate and distinct steps, and are carried out by separate and distinct parts of the apparatus provided for the performance of my process. In either case the process is a continuous one, for the 90 highly heated and cracked constituent is being continuously added to the larger mass of cooler liquid hydrocarbon, thus producing a mixture which contains, and from which the lighter and more volatile hydrocarbons 95 100 may be separated. The actual separation of such light products by a distillation process is or may be continuous in the case where such process is carried out in the receptacle in which the mixing occurs, and by the inherent heat which the mixture attains when the process has been in operation for a while; and the distillation step is or may likewise be made continuous if the mixed liquid is withdrawn from the mixing receptacle and 105 110 distilled in a separate distilling apparatus.

Various particular forms of apparatus may be employed in performing my improved process, some of which are illustrated in the drawings accompanying and forming a 115 part of this specification; although it will be appreciated that forms of apparatus other than those illustrated may be employed, so long as they are suitable for use in performing the various steps or operations in which my improved process consists.

In the said drawings—

Figure 1 is a view showing in a conventional manner an apparatus in which the heating of the relatively small quantity of 125 liquid hydrocarbon is accomplished by means of a plurality of gas heated heating devices located within the receptacle containing the relatively large volume of liquid hydrocarbon, this view being a section taken 130

upon a plane indicated by the line 1—1, Figure 2;

Figure 2 is a view showing a section taken upon a plane indicated by the line 2—2, 5 Figure 1;

Figure 3 is a view showing a conventional form of apparatus in which the heating of the relatively small volume of liquid hydrocarbon to crack the same is provided for by 10 the use of a furnace located outside the receptacle containing the relatively large volume of liquid hydrocarbon;

Figure 4 is a view illustrating a form of apparatus in which the heating of the portion 15 of the liquid hydrocarbon which is cracked is accomplished by the use of an inductive electrical heating device;

Figure 5 is a view similar to Figure 3, but showing a modified form of heating means;

Figure 6 is a view showing in a conventional manner an apparatus in which the heating is accomplished by an electrically heated resistance element located within the receptacle containing the larger volume of 25 liquid hydrocarbon with which the heated liquid hydrocarbon is mixed; and,

Figure 7 is a view showing a conventional form of apparatus in which the liquid hydrocarbon being heated, as well as that with 30 which the heated portion is mixed is in the form of a spray, the heating being accomplished by an electrically heated resistance element.

Referring now to the drawings, and first 35 to the form of my invention illustrated in Figures 1 and 2 thereof, the reference numeral 10 designates a suitable receptacle or container of any desired form; the same being designed to contain the liquid hydrocarbon operated upon in the performance of 40 my process, and of large capacity as compared with the amount or volume of liquid hydrocarbon being heated at any given time to a cracking temperature.

Located within the receptacle or container 45 10 is a plurality of heating members, each designated as a whole by the reference numeral 11, whereby the small portion of the liquid hydrocarbon which is heated to such 50 a temperature as to crack it in performing my process is heated to a comparatively high temperature, to thereby crack the liquid thus heated, and decompose the same into liquid hydrocarbons having a lower boiling point 55 than that of the original liquid hydrocarbon subjected to my process. It will be obvious, however, that a greater or less number of heating elements than the number illustrated may be employed, as my invention is 60 in no way concerned with a particular number of heating devices employed in a given apparatus.

Each of the heating devices above referred to is shown as made up of a metallic tube 12 65 arranged in an inclined position and extend-

ing from one side to the other of the receptacle 10, within which tube a heating element in the form of a gaseous fuel burner 13 is located, to thereby heat the tube, as will be appreciated, a suitable outlet flue or chimney 14 being provided at the upper end of 70 each tubular member through which the products of combustion may pass. Surrounding the tubes 12 are tubes 15 made,

preferably, of non-conducting material, such 75 as porcelain, fire clay, or similar material; which outer tubes are spaced apart somewhat from the metallic tubes 12 to thereby

provide an annular heating space 16 between the two tubes. Provision is made for 80 the flow of a stream of liquid hydrocarbon from the main body of liquid contained in the receptacle 10 into the annular space between the two tubes, along or through said

space, and out therefrom and into the main 85 body of liquid hydrocarbon; so that a continuous circulation of the liquid being thus heated to a cracking temperature will be maintained; this being provided for in the

form of my invention illustrated by openings 90 17 provided in the outer tube and located adjacent the lower end thereof, and through which the cool liquid may flow into the annular space, and other openings 18

located adjacent the upper end of the tube and through which the heated liquid may flow from the said space and return to the main body of liquid within the receptacle 10. 95

It will therefore be appreciated that when 100 the device is in operation and the tube 12 is being heated as above explained, a continuous flow of that portion of the liquid hydrocarbon being treated which at any particular instant is being heated to a cracking

temperature, will flow from the main body 105 or mass of liquid contained in the receptacle 10 into the annular space between the tubes 12 and 15, upwardly through and along the passage between said tubes, and out from

between said tubes at the upper ends thereof; whereupon the liquid which is thus heated returns to the main body of liquid and 110 becomes mixed therewith and more or less completely dispersed throughout the mass thereof.

The temperature of the heating devices will be so regulated that the liquid flowing through the annular heating space referred to will be cracked to a greater or less and to the desired extent; the degree of cracking being dependent upon the temperature 115 of the heating tube 12, upon the character of the liquid hydrocarbon being treated, and upon various other circumstances well recognized by those skilled in the art

and which need not be here enumerated. In 120 each case the adjustment of the apparatus will be such as to produce the largest possible quantity of the particularly light hydrocarbons which it is desired to produce,

as will be appreciated. 125

130

The portion of the liquid flowing through the annular space 16 which is actually cracked by the heating action to which it is subjected in the performance of my process, 5 as well also as the portion of the said liquid which in practice is not actually cracked, return to and mix with the main body of the liquid hydrocarbon in the receptacle 10, the temperature of which is much lower than 10 the cracking temperature to which the liquid being heated is actually heated. This low temperature of the main body of the liquid subjected to my process is a natural concomitant of the mixing of relatively 15 small volumes of liquid, even though they may be at a high temperature, with a very much greater volume of liquid which is cool at the beginning of the process, which is exposed to radiation, and to which a fresh supply 20 of cool liquid is commonly being supplied continuously or frequently; and the use of the outer tube 15 of non-conducting material whereby the heat generated within and conducted to the exterior of the metallic 25 tube 12, and to the liquid hydrocarbon flowing through the annular space 16, is not communicated or conducted to the main body of liquid, obviously contributes to the keeping of the main body of liquid at a 30 comparatively low temperature. The main body of liquid within the chamber 10, may, if found necessary, be cooled and its temperature thereby more positively regulated and kept materially below the temperature of 35 the portion of the liquid which is being heated by the heating devices, by the use of separate and independent cooling means provided for that purpose; as it is obvious that the continuous mixing of the liquid 40 which is heated to the cracking temperature with that in the receptacle 10 will cause the temperature of the latter to rise, and that such temperature might, if uncontrolled, rise to too high a point.

45 It therefore follows that the cracked products produced by the heating members are carried away from the zone at which heating and cracking occurs by the stream of heated liquid, and that the uncracked portion of the heated liquid as well as the portion 50 thereof which is cracked by the heat to which it is subjected are immediately mixed with the main body of cooler liquid within the chamber 10 while the cracked products 55 are in a nascent state, and before they have had time to vaporize and become free of or to separate from the uncracked portion of the heated liquid with which they are associated; the said products being thus condensed, dissolved in, reabsorbed into, or 60 otherwise incorporated with and dispersed throughout the much larger body of relatively cool hydrocarbon into which the heated liquid enters and with which it mixes.

65 This mixing of the heated constituent of

the liquid operated upon with the cooler main portion thereof, and the consequent cooling of the said heated portion to a temperature below the cracking temperature to which it was subjected, arrests the cracking action and prevents decomposition of the cracked products, or over cracking, or the continuation of the cracking action after it may be desirable to terminate the same. The cracking action is thus controllable in 70 my process, and may be regulated and varied in such a way as to secure uniformity in the product obtained to a greater extent than has heretofore been the case; furthermore, the process may be regulated with reference to and in such a way as to produce cracked products having definite and predetermined characteristics, for the properties of the cracked products depend upon the temperature employed, the duration of 75 the heating action or rate of flow of the stream of liquid being heated, and other circumstances all of which are under the control of the operator.

The main body of liquid hydrocarbon 80 within the receptacle 10 obviously becomes more or less heated after the process has been in operation for a time, although as stated the temperature of said liquid is always materially below the temperature to which the small portion of liquid separated or differentiated from the main body thereof is heated to thereby crack the same. This heating of the main body of liquid will obviously result in the vaporization of some of the 85 lighter and more volatile hydrocarbons produced, which action, however, will rapidly build up a pressure within the receptacle 10 above the liquid therein, which will arrest such action and prevent the further vaporization of the cracked products produced.

In certain cases I find it desirable to subject the liquid within the receptacle 10 to a gas pressure other than that due to the vaporization of cracked products produced, 90 and greater than the vapor tension of the liquid contained therein at the temperature of the said liquid, to which end I have illustrated a tube 19 leading from a reservoir 20 containing a liquefied gas or a gas compressed to a high pressure, to the receptacle 10 and discharging thereinto above the surface of the liquid, whereby the liquid hydrocarbon within the receptacle 10 may be subjected to a gas under pressure derived from the receptacle 20; the gas employed preferably being nitrogen, carbon di-oxide, hydrogen or other gas. This arrangement provides for the regulation of the gas pressure 95 above the liquid throughout a wide range, and for controlling the vaporization of the cracked products from the mass of liquid in which they are held; and provides also for regulating the character of the cracked products produced, for the boiling point and 100

other characteristics of the said products are largely dependent upon the pressure conditions under which they are produced.

In the working of my process it will often be found desirable to subject the liquid within the container 10 to gas pressure as above at the beginning of the process, after which and when the body or liquid within the receptacle has become heated, the supply of gas from the container 20 may be discontinued, the pressure to prevent the vaporization of the cracked products being thereafter maintained by the vaporization of a small portion of the lighter and more volatile 10 of the said products.

It will be appreciated that after my improved process has been in operation for a time the body of liquid hydrocarbon within the receptacle 10 will contain the cracked 20 products which have been thus far produced, as hereinbefore explained, the amount of such products within the mass of liquid being obviously dependent upon the length of time the process has been in operation, and 25 the temperature to which the liquid flowing past the heated device has been heated; or, as otherwise stated, upon the degree or extent of cracking produced by the heating means. These light or volatile products will 30 be removed from the mass of liquid by subjecting the same to a distillation process, which process may be carried on either in the receptacle 10 or in a still separate and distinct from the said receptacle. The distillation may be fractional whereby cracked 35 products having different boiling points are separated from one another, or all said products boiling above a predetermined temperature may be collected as a single liquid.

40 In case the distillation of the volatile products produced in the operation of my process is to be conducted in the receptacle 10, such distillation will preferably be accomplished by the heat of the mass of liquid 45 contained within the receptacle; it being obvious that the said mass of liquid will, after the process has been in operation for a time, have become heated to a temperature above the boiling point of the cracked hydrocarbons produced in the performance of the 50 process and which are contained in the said liquid. In distilling in accordance with this scheme it is only necessary to provide an outlet conduit 21 leading from the receptacle 10, which conduit is cooled by a condenser 22; whereby the vapors of the cracked hydrocarbons driven off from the main body 55 of liquid are condensed and a liquid cracked product thereby secured, said conduit 21 being preferably provided with a valve 221 for controlling the flow therethrough and regulating the pressure within the receptacle 10. Ordinarily the discharge of condensed cracked liquid products from the condenser, 60 or the flow of vapor from the receptacle 10,

will be regulated and restrained by means of a suitable pressure regulating valve; in order to thereby increase the back pressure within the receptacle and secure the distillation of the cracked products at a temperature somewhat higher than that at which they boil at atmospheric pressure. 70

Instead, however, of distilling with the receptacle 10 I may withdraw the liquid therefrom through the conduit 23 or 23' leading to a still 24 of any suitable form and construction, and within which the liquid is distilled; the lighter hydrocarbons passing from the still through a conduit 25 controlled at its outlet end by a valve 251, and 80 the same being condensed by a cooler 26 as in ordinary distilling and condensing operations. As a matter of practice I prefer to use both methods of distillation at one and the same time, as it is more convenient 85 and in other respects advantageous to conduct such of the cracked products as are vaporized under the temperature and pressure conditions present in the receptacle 10 therefrom through a conduit controlled by a 90 pressure regulating valve to thereby control the pressure within the said receptacle, and condense the said products by means of a cooler like the cooler 22; while at the same time providing for the removal of liquid 95 from the receptacle 10, which liquid obviously contains cracked products which are not vaporized under the temperature conditions existing in the said receptacle, into a separate still like the still 24 wherein they 100 may be subjected to a different temperature than that of the main body of liquid within the receptacle 10.

It will be appreciated that my improved process is a continuous one in that cracked 105 products are being continuously produced by the heating member or device, and continuously added to the main body of liquid within the receptacle 10, thus providing a mass or body of liquid containing cracked 110 products and from which they may be recovered.

The cracked products may in whole or in part be permitted to flow as vapors and continuously from the receptacle 10 through the conduit 21, to be condensed and recovered by the cooler 22, in which case it follows that the cracking of a mass of liquid introduced into the container may be continued or carried on until the residue is of such a 115 character that it may no longer be effectively cracked, because of the fact that the residue or uncracked part of any particular differentiated portion of the liquid flowing through the annular space 16 at a given instant may again flow through said space after it has been returned to and mixed with the main body of liquid, and after the cracked products produced in the said portion have been separated therefrom. 120 125 130

I prefer, however, to provide for the supply of fresh and untreated liquid hydrocarbon to the receptacle 10, to which end a supply pipe 27 leads thereinto through which fresh liquid hydrocarbon may be supplied; and, in order to insure that the liquid will be effectively subjected to the action of each of the several heating devices, I preferably provide 10 baffle plates 28 within the receptacle 10 for causing the liquid to flow past the several heaters 11 in succession. When operating with a constant or substantially constant supply of fresh and untreated liquid hydrocarbon, as will usually be the case, the process and apparatus will be so regulated that the residue from the still 24 will be a heavy hydrocarbon having a high boiling point, and one which it is not desirable to subject 15 anew to a cracking process.

In the form of apparatus illustrated in Figure 3, a receptacle 28 similar to the receptacle 10 is provided for containing the mass of liquid hydrocarbon operated upon. 25 Communicating with this receptacle is a heating loop made up of metallic pipes 29, 30, 31 whereby a circulation of liquid hydrocarbon from the receptacle 28 through said pipes and back to the said receptacle, is 30 maintained; which pipes pass through and are heated by a suitable furnace 32 so that the heating is accomplished by heating means located outside of the receptacle which contains the liquid being operated upon. In 35 this form of apparatus the liquid hydrocarbon is supplied to the receptacle through a conduit 33 which communicates with an equalizing chamber 34 to which liquid hydrocarbon is supplied by a pump 35, and 40 into which chamber a conduit 36 leading from a source of gas under pressure discharges; and by means of which device liquid hydrocarbon may be supplied under pressure to the said receptacle 28. The 45 heating tubes preferably contain deflectors 37 made of non-conducting material, such as porcelain, the purpose of which is to cause the liquid being heated to flow adjacent the wall of the tubes whereby the liquid is 50 more effectively heated.

Figure 4 shows a form of apparatus in which the heating of the portion of liquid hydrocarbon subjected to the cracking operation is accomplished by means of a loop 55 38 made of hollow piping and the ends of which communicates with a receptacle 39 containing the liquid hydrocarbon being treated, and the ends of which loop are also preferably connected by an independent 60 conductor 40 whereby the loop and conductor form a secondary coil, made up of a single turn, of a transformer; the iron core of which is indicated at 40' and the primary coil of which is shown at 41. It therefore 65 follows that upon passing an alternating

current through the primary 41, the secondary made up of the pipe 38 will be heated to a high temperature by induction, thus providing for the cracking of the liquid hydrocarbon flowing through the said tube. 70

Figure 5 shows a form of apparatus in which the heating of the liquid hydrocarbon subjected to the cracking temperature is accomplished by means of a gas heated furnace 42 in which a loop 43 is located, and 75 the ends of which loop communicate with the receptacle 44 which contains the main body of liquid hydrocarbon being treated.

Figure 6 shows a form of apparatus in which the heating of the liquid is accomplished by means of an electrical heater 45 located within the receptacle 46, said heater being shown as made up of an outer tube 47, an inner core 48 and a tubular resistance member 49 spaced apart from both said last 80 mentioned members whereby annular passages are provided; and which resistance member is heated electrically by a current of electricity conveyed thereto through an insulated terminal 50 and a second terminal 51 85 connected with the wall of the receptacle, one end of the heating element 49 being connected with the wall of the receptacle as shown at 52. The members 47 and 48 are made of insulating material in order to prevent short circuiting, and to also provide heat insulation whereby the heating of the liquid within the receptacle 46, except by the mixture therewith of the portion of the liquid subjected to the cracking temperature, is avoided. 90

Figure 7 shows a form of apparatus in which the liquid hydrocarbon is in a finely divided form during the heating of the portion thereof which is subjected to the cracking temperature, and when the heated and cracked products thus produced are mixed with the larger volume of unheated liquid. In the apparatus there illustrated the hydrocarbon being subjected to my process passes 105 from a chamber 53 through an outlet conduit 54 having a nozzle or rose at its lower end, whereby the liquid is finely divided and a spray produced, said rose being located in a closed chamber 56. Located below the nozzle 55 is a heater 57 which may be in various forms, but which is here shown as an electric heater, the said heater being in the path of the finely divided or sprayed liquid issuing from the nozzle or rose 55. 110 Such being the case it will be obvious that the portion of the sprayed liquid closely adjacent the heater 57 will be heated to a high temperature and cracked, while the portion thereof more remote from the heater will 125 not be subjected to such heating and cracking operation. Both the heated and cracked, and the unheated liquid pass downward through the chamber 56 and become mixed with one another at the lower portion there- 130

of where they accumulate, and from which chamber they pass through conduit 58 into a receiving receptacle 59. The product which collects in this last mentioned receptacle is obviously made up of a small volume of liquid hydrocarbon which has been highly heated and a portion of which has been cracked, together with a larger volume of liquid hydrocarbon which has not been subjected to the cracking temperature, the same as in the case of the receptacles in the various forms of apparatus heretofore described, and the temperature of which mixture is obviously low as compared with the temperature to which the smaller portion of the liquid hydrocarbon is heated during the cracking step. This mixed liquid hydrocarbon is withdrawn from the receptacle 59 through a conduit 60 and treated to a distillation process in any suitable still, as hereinbefore explained.

In view of the premises it will be appreciated that in the working of my improved process the entire mass or body of liquid hydrocarbon with which the process is concerned at any given time may properly be regarded as made up of two parts, the greater of which within the receptacle 10 is many times the volume of the lesser part being heated to a cracking temperature by the heating device; and that the liquid hydrocarbon which is being heated is isolated from the main body of liquid operated upon but is, immediately after being heated, added to and mixed with the much greater mass of the main body of liquid above referred to and the temperature of which is lower than the temperature to which the lesser mass is heated.

The cracked products produced in the portion of the liquid being heated are obviously in a gaseous state, or in a condition to assume that state, because of the high temperature employed for cracking the liquid; but no attempt is made to separate them from such liquid as may not be cracked while they are in the nascent state in which they must necessarily exist at or immediately after the instant that they are produced. On the contrary, the said gaseous or incipiently gaseous products are prevented from separating, physically, from the liquid from which they are produced by immediately discharging both the cracked and uncracked heated liquid into the greatly excess volume of cooler liquid, whereby the cracked products are, before they have had an opportunity to separate as a gas or vapor, condensed and absorbed into and become dispersed throughout the greater mass of comparatively cool liquid; the cracked volatile products being subsequently recovered from the large volume of liquid in which they are absorbed by a distillation process performed upon the entire mass thereof, as

distinguished from keeping or attempting to keep the cracked products in the gaseous or vaporous form in which they are produced, collecting them in that state and finally condensing the vapor.

The pressure to which the liquid hydrocarbon operated upon is preferably subjected prevents the cracked and volatile products from separating from the liquid from which they are produced until the mixing of said liquid with the larger body of liquid has been consummated, restrains the vaporization of the cracked products and determines the temperature at which they will be driven off from the mass of liquid throughout which they are dispersed, and determines the character of the cracked products resulting from the heating action as the properties of the said products depend upon the temperature and concomitant pressure conditions present at the place where the cracking occurs. The process may therefore be controlled and regulated both as to the purely physical phenomena associated therewith and as to the character or properties of the cracked products produced by regulating the pressure to which the liquid hydrocarbon operated upon is subjected.

The temperature to which the small volume of liquid which is being continuously heated while it is separated from the main mass of liquid is heated will be a temperature sufficient to accomplish the cracking of the hydrocarbon being treated, and will vary both with the character of the liquid being treated and the character or boiling point of the product desired. As a general average a temperature of 650 degrees Fahrenheit or upward will accomplish the cracking of most hydrocarbons, and will produce a product sufficiently volatile to take the place of or be used with ordinary gasoline.

It will be appreciated, however, that the temperature of the main body of liquid never rises to the cracking temperature. Its volume is large as compared with that of the liquid being cracked, and the liquid being cracked is heated under conditions designed to minimize the direct communication of heat to the main mass of liquid. The main body of liquid is to be sure heated by the small volume of cracked hydrocarbon discharged thereinto to accomplish the sudden cooling of the cracked portion, but as hereinbefore pointed out the temperature of the main volume is kept substantially lower than the temperature best suited for cracking the hydrocarbon operated upon. A temperature of 650 F. or above will ordinarily be used to accomplish the cracking of the small volume subjected to the cracking temperature; the temperature of the main mass should be kept as low as

as possible, as the process is the more effective the more sudden the cooling of the cracked portion discharged into the main mass of liquid undergoing treatment; and the temperature of the main mass of hydrocarbon ought to be kept at least 250 or 300 degrees Fahrenheit below the cracking temperature.

It will be appreciated that whereas a high temperature is commonly necessary to accomplish the cracking of a liquid hydrocarbon, the temperature at which the resulting product vaporizes is very much lower, in fact several hundred degrees lower in most cases. My process takes advantage of this fact and avoids, and in fact prevents to as great an extent as possible, the heating of the entire mass of liquid being treated up to the cracking temperature, as has heretofore commonly been the case; thus providing a process wherein the cracking is accomplished by the heating of a small isolated and continuously renewed mass of liquid, which to be sure is heated to the cracking temperature, but in which the main body or mass of liquid being treated is kept at a temperature several hundred degrees below the cracking temperature.

Having thus described and explained my invention, I claim and desire to secure by Letters Patent:

1. In a device for cracking liquid hydrocarbons, a closed receptacle of relatively large capacity adapted to contain a liquid hydrocarbon; heating means located within said receptacle; means for causing a stream of liquid hydrocarbon of relatively small volume as compared with the volume of liquid contained within said receptacle to flow from the body of liquid contained therein past said heating means, and back into the relatively large mass of liquid contained within said receptacle; a source of gas under pressure; a conduit leading from said source and discharging into said receptacle to thereby create a gas pressure therein, and control the vaporization of the cracked products present in the liquid within said receptacle; and means whereby the liquid hydrocarbon not heated as aforesaid is maintained in a relatively cooled condition.

2. The process of treating liquid hydrocarbon which consists in heating a relatively small quantity of liquid hydrocarbon to a temperature sufficient to crack the same; mixing said heated liquid immediately, and without separation of the lighter products produced by such heating therefrom, with a relatively large quantity of liquid hydrocarbon the temperature of which is maintained throughout such heating operation at a temperature substantially below the temperature to which the small quantity of liquid hydrocarbon is subjected; and removing the

lighter products from the mixture thus produced by distilling the said mixture.

3. The process of treating liquid hydrocarbon which consists in providing a relatively large volume of liquid hydrocarbon; isolating a relatively small quantity of said liquid hydrocarbon; heating the small volume of liquid hydrocarbon thus isolated to a temperature sufficiently high to crack the same; discharging the said heated liquid into the large body of liquid aforesaid below the surface thereof immediately, and without separation of the lighter products produced by such heating therefrom; maintaining the temperature of said large body of liquid materially below the temperature to which said small volume of liquid hydrocarbon is heated; and removing the lighter products from the mixture thus produced by distilling the said mixture.

4. The process of treating liquid hydrocarbon which consists in providing a relatively large volume of liquid hydrocarbon; continuously removing relatively small quantities of said liquid hydrocarbon from the main body thereof; continuously heating the liquid hydrocarbon thus removed and while it is isolated from the main body of liquid hydrocarbon to a temperature sufficiently high to crack the same; continuously returning the heated liquid hydrocarbon to the main body of liquid hydrocarbon at a point below the surface thereof; maintaining the temperature of said large body of liquid materially below the temperature to which said small quantities of liquid hydrocarbon are heated; and subjecting the said mixture to a distilling process to thereby separate the lighter hydrocarbons produced by the heating step aforesaid therefrom.

5. The process of treating liquid hydrocarbon which consists in providing a relatively large volume of liquid hydrocarbon; continuously removing relatively small quantities of said liquid hydrocarbon from the main body thereof; continuously heating the liquid hydrocarbon thus removed and while it is isolated from the main body of liquid hydrocarbon to a temperature sufficiently high to crack the same; continuously returning the heated liquid hydrocarbon to the main body of liquid hydrocarbon at a point below the surface thereof; keeping the temperature of said mixture substantially below the temperature to which said small quantities of liquid are heated; and subjecting the said mixture to a distilling process to thereby separate the lighter hydrocarbons produced by the heating step aforesaid therefrom.

6. The process which consists in providing a relatively large mass of liquid hydrocarbon; isolating a relatively small quantity of said mass of liquid hydrocarbon heating

the same to a cracking temperature; and discharging the said small quantity of heated liquid into the large mass of liquid aforesaid immediately, and without separation of 5 the lighter products produced by said heating action therefrom; and maintaining the mass of liquid hydrocarbon not heated as aforesaid at a temperature substantially lower than the temperature to which said 10 small quantity of liquid hydrocarbon is heated.

7. The process which consists in providing a relatively large mass of liquid hydrocarbon; isolating a relatively small quantity 15 of said mass of liquid hydrocarbon and heating the same to a cracking temperature; discharging the heated liquid into the large mass of liquid aforesaid below the surface thereof immediately, and without separation 20 of the lighter products produced by said heating action therefrom; continuously replacing the liquid heated as aforesaid by liquid derived from said relatively large mass of liquid; and maintaining said relatively large mass of liquid at a temperature 25 below that to which said relatively small mass is heated.

8. The process which consists in providing a relatively large mass of liquid hydro- 30 carbon; isolating a relatively small quantity of said mass of liquid hydrocarbon and heating the same to a cracking temperature; permitting a movement of the heated liquid into the large mass of liquid aforesaid below the 35 surface thereof immediately, and without separation of the lighter products produced by said heating action therefrom; continuously replacing the liquid heated as aforesaid by liquid derived from said relatively 40 large mass of liquid; maintaining said relatively large mass of liquid at a temperature below that to which said relatively small mass is heated; and subjecting said large 45 mass of liquid to a gas under pressure to thereby restrain the evaporation of volatile products therefrom.

9. The process which consists in providing a relatively large mass of liquid hydrocarbon; isolating a relatively small quantity 50 of said mass of liquid hydrocarbon and heating the same to a cracking temperature; discharging the heated liquid into the large mass of liquid aforesaid below the surface thereof immediately, and without separation 55 of the lighter products produced by said heating action therefrom; continuously replacing the liquid heated as aforesaid by liquid derived from said relatively large mass of liquid; maintaining said relatively

large mass of liquid at a temperature below 60 that to which said relatively small mass is heated; subjecting said larger mass of liquid to a gas under pressure; and subjecting the mixture produced by the continual discharge of the heated liquid containing cracked 65 products into the larger mass of liquid to a distilling operation, to thereby separate the lighter products from the said mixture.

10. The process which consists in providing a relatively large mass of liquid hydro- 70 carbon; isolating a relatively small quantity of said mass of liquid hydrocarbon and heating the same to a cracking temperature; discharging the heated liquid into the large mass of liquid aforesaid below the surface 75 thereof immediately, and without separation of the lighter products produced by said heating action therefrom; continuously replacing the liquid heated as aforesaid by liquid derived from said relatively large 80 mass of liquid; maintaining said relatively large mass of liquid at a temperature below that to which said relatively small mass is heated; and distilling the mixture produced by the continual discharge of the heated liquid 85 containing cracked products into the larger mass of liquid by means of the heat thus acquired by said larger mass, to thereby separate the lighter products from said mixture.

11. The process which consists in providing a relatively large mass of liquid hydrocarbon; isolating a relatively small quantity 90 of said mass of liquid hydrocarbon and heating the same to a cracking temperature; discharging the heated liquid into the large mass of liquid aforesaid below the surface 95 thereof immediately, and without separation of the lighter products produced by said heating action therefrom; continuously replacing the liquid heated as aforesaid by liquid derived from said relatively large 100 mass of liquid; maintaining said relatively large mass of liquid at a temperature below that to which said relatively small mass is 105 heated; subjecting said larger mass of liquid to a gas under pressure; and distilling the mixture produced by the continual discharge of the heated liquid containing cracked 110 products into the larger mass of liquid by means of the heat thus acquired by said larger mass, to thereby separate the lighter products from said mixture.

In testimony whereof, I have signed my name to this specification this 7th day of 116 August, 1918.

GEORGE L. HOXIE.
